J. ABRAMOWITZ,
ARCH SUPPORT.
APPLICATION FILED JAN. 31, 1921.

Patented May 30, 1922.

FIG. 2

FIG. 3

FIG. 4

FIG. 5

INVENTOR

JOSEPH ABRAMOWITZ,
by Raphael Koenig ATTORNEY.

UNITED STATES PATENT OFFICE.

JOSEPH ABRAMOWITZ, OF MADISON, ILLINOIS.

ARCH SUPPORT.

1,418,048.

Specification of Letters Patent. Patented May 30, 1922.

Application filed January 31, 1921. Serial No. 441,385.

To all whom it may concern:

Be it known that I, JOSEPH ABRAMOWITZ, a citizen of the United States, residing at Madison, county of Madison, and State of Illinois, have invented a certain new and useful Improvement in Arch Supports, of which the following is a specification, reference being had to the accompanying drawings, forming a part thereof.

This invention relates to a certain new and useful improvement in arch-supports, the principal object of my present invention being to provide, as a new article of manufacture, an arch-support of simple, durable, and inexpensive construction which will act or function to adapt or build up a shoe or other foot-wear to properly and comfortably support the metatarsus or instep of the foot, and at the same time serve to automatically cause a beneficial circulation of air within the shoe.

With the above and other objects in view, my present invention resides in the novel features of form, construction, arrangement, and combination of parts hereinafter described and afterwards pointed out in the claims.

In the accompanying drawing:

Figure 1 is an elevational view of an arch-support embodying my invention, showing by dotted lines its disposition in a shoe;

Figure 2 is a transverse sectional view of the arch-support, taken approximately on the line 2—2, Figure 1;

Figure 3 is a longitudinal sectional view of the arch-support taken approximately on the line 3—3, Figure 2;

Figure 4 is a plan view of the support; and

Figure 5 is an end elevation of a slightly modified form of arch-support embodying my invention.

Referring now more in detail to the said drawing, which illustrates a practical embodiment of my invention, and in which like reference characters refer to like parts throughout the several views, 1 indicates the base of the support, which is formed or constructed of suitable preferably resilient material, such as sheet metal, and shaped and contoured to conveniently fit within a shoe at its shank and heel, as best seen in Figure 1. 2 indicates the support proper, which is of a size and contour to likewise conveniently fit within the shoe, and which not only normally inclines transversely, that is to say, is

higher relatively to the base 1 at its inner margin than at its outer margin, but is also bodily both longitudinally and laterally shaped to approximately conform to and provide a support for the arch of the human foot.

By preference, the base 1 and the support proper or portion 2 are constructed from a single blank of sheet metal, with one edge 65 of their side margins integrally joined or connected, as at 3, Figure 2; but such parts of the support may be of separate sections riveted or otherwise fastened operatively together as shown in Figure 5, wherein the base 1' is flanged at a side margin to extend for securement, as at 3', over and upon the adjacent so-called outer margin of the support proper 2'.

The upper element or support proper 2 is 75 normally obliquely spaced from the lower or base element 1 a distance greater than is required in the device for a proper arch support, and due to the tension or spring inherent in the material of the joint or connection 3 between the lower and upper elements 1 and 2, respectively, the upper element 2 becomes not only a self-adapting support for the metatarsus or arch when the weight of the foot and body is applied, but at the same time rises and falls relatively to the base 1 on each application and relief of the weight of the foot, as in walking, and thus, at each "step" also acts as a "bellows" to create a circulation of air within the shoe, 90 the arch-support in such manner additionally serving toward keeping the foot cool and the shoe and the hose dry.

The arch-support is usually provided with a relatively soft covering or pad 4 of leather 95 or other suitable material and in order that the pad 4 may be maintained in proper relation with the support-proper 2, I preferably provide the support-element 2 with pad holding-means, such as the "points" 5, which may be economically provided in the metal element 2 by punching.

My new arch-support may be inexpensively manufactured, may be made in various shapes and sizes to fit shoes of different sizes 105 and to accommodate arches or insteps of various contour, and has been found from use exceedingly efficient in performing its intended functions.

I am aware that changes in the form, construction, arrangement, and combination of the several parts of the arch-support may

be made and substituted for those herein shown and described without departing from the nature and principle of my invention.

5 Having thus described my invention, what I claim and desire to secure by Letters Patent is:

1. An arch-support comprising a base adapted to fit within a shoe, an arch-supporting element also contoured to fit within a shoe and shaped to conform approximately to the instep or arch of the foot, and a sheet metal hinge connection between the base and one side margin only of the arch-supporting element and yieldingly maintaining the arch-supporting element normally in obliquely disposed spaced relation to the base, the arch-supporting element being otherwise out of engagement with the base and adapted through the inherent resiliency of said hinge connection to yieldingly rise and fall

relatively to the base on each application and relief of the weight of the foot.

2. As a new article of manufacture, an arch-support formed of a single section of sheet metal and integrally comprising a base and an arch-supporting element both contoured to fit within a shoe and the arch-supporting element being shaped to conform approximately to the instep or arch of the foot, the arch-supporting element being normally disposed obliquely to the base and integrally joined to the base at one side margin only, the supporting element being otherwise out of engagement with the base and being adapted to resiliently rise and fall relatively to the base on each application and relief of the weight of the foot.

In testimony whereof, I have signed my name to this specification.

JOSEPH ABRAMOWITZ.
